UNITED STATES PATENT OFFICE.

BURT A. PETERSON, OF ROCKFORD, ILLINOIS, ASSIGNOR, BY MESNE ASSIGNMENTS, TO BARBER-COLMAN COMPANY, OF ROCKFORD, ILLINOIS, A CORPORATION OF ILLINOIS (1922).

KNOTTER.

Application filed April 1, 1920, Serial No. 370,394. Renewed April 2, 1924.

To all whom it may concern:

Be it known that I, BURT A. PETERSON, a citizen of the United States, residing at Rockford, in the county of Winnebago and 5 State of Illinois, have invented certain new and useful Improvements in Knotters, of which the following is a specification.

The invention relates to knot-tying implements of the type employed in textile mills for uniting the ends of thread or yarn; and the object of the invention is to provide a knitter of a practical character, constructed almost wholly of sheet metal, so that it may be cheaply manufactured, 10 but made sufficiently rugged to withstand the hard usage to which such devices are subjected.

The embodiment of the invention illustrated in the accompanying drawings is intended to be illustrative only, it not being intended that the invention shall be limited in the interpretation of the appended claims to the particular construction and arrangement hereinafter fully described except as may be necessitated by the state of 20 the prior art.

Figure 1 of the drawings is a side elevation of my improved knitter, the strap, by means of which the device is secured to the 25 hand of the operator, being omitted. Fig. 2 is a central vertical section through the knitter. Figs. 3 and 4 are vertical sectional views taken respectively on lines 3-3 and 4-4 of Fig. 2. Figs. 5 and 6 are 30 respectively perspective views of a driving and driven yoke for actuating parts of the tying mechanism. In the drawings, for the sake of clearness the invention is illustrated on a scale approximately twice its actual size.

The knitter comprises, generally, a relatively stationary annular casing 8 having rotatably mounted diametrically thereof a stem or spindle 9, said spindle carrying at one end a tying-bill 10 and having rigid therewith a pinion 11. Mounted to swing coaxially of the annular casing 8 are two yokes 12 and 13. The yoke 12 is arranged to be swung manually in one direction by 40 means of an operating lever 14 and the yoke 13 is mounted to be swung in a direction opposite to that of the yoke 12 through the rotation of the pinion 11 effected by the swinging of the yoke 12. Operatively associated with the yoke 13 so as to be swingable

therewith is a clamping stripper 15 which together with a guide member 16 is adapted to hold the threads or yarn to be united by rotation of the tying-bill 10. The clamping stripper is adapted to be actuated in 60 the operation of the knitter so as to clamp the threads therein by means of a stationary cam member 17 operatively associated with the clamping stripper 15. For actuating the yoke 12 and associated parts in 65 the direction opposite to that in which it is moved by the operating lever 14, I provide a coiled spring 18.

The annular casing 8 may be of any suitable or preferred construction. Herein it 70 comprises a main cup-shaped portion 8^a and a cap portion 8^b detachably secured to the main portion as by means of a bowed spring member 8^c formed of wire and having opposite ends 8^d bent outwardly so as 75 to project through registering openings in the two overlapping portions of the casing. In one side of the casing is provided an opening surrounded by an outwardly extending flange 19 forming a bearing for the 80 lower end of the spindle 9, and diametrically opposite said opening is an opening 20 through which extends the tying-bill 10. On the inner side of the casing adjacent the opening 20 is fixed a bearing bracket 21 85 through which the spindle 9 projects.

The tying-bill may be of any usual or preferred construction being herein of the type disclosed in Patent No. 755,110, dated March 22, 1904, the bracket 21 in the casing being constructed to provide a cam barrel arranged to actuate the clamping and shearing mechanism of the bill, in a 90 well known manner.

Mounted co-axially of the casing 8 in 95 the opposite walls thereof are a rotatable stem 22 and a fixed stud 23, respectively. On said stem and stud 23 is mounted the driving yoke 12, which is preferably formed 100 of sheet metal. One of the arms of the yoke is rigid with an annular flange 24 formed on the pivotally-mounted stem 22, being preferably welded thereto, and the other arm of the yoke is rotatably mounted upon a journal 25 provided by the stud 23. Connecting the arms of the yoke 12 is a curved or arcuate plate or member 12^a which is cut away throughout the greater portion of its 105 length to provide a slot 26. One edge of said slot is provided with gear teeth 27, 110

thus forming a gear segment which is adapted to mesh with the teeth of the pinion 11. As herein shown the pinion 11 may be formed integrally with the spindle 9.

5 The yoke 13 is similar to the yoke 12 in shape but of a size to permit of its entrance within the yoke 12. One arm of this yoke 13 is rotatably mounted upon a journal provided by the head 28 of a screw 29 entered within the stem 22 from the inner end thereof; while the other arm of the yoke 13 is mounted upon a journal 30 provided by the stud 23 inwardly of the journal 25 of said stud. Said journal 30 of the 10 stud is preferably extended inwardly a short distance so as to project into a groove 9^a formed in the spindle. The stud thus serves to hold the spindle against longitudinal movement when the cap 8^b of the 15 casing is in position. Around the openings in the arms of the yokes 12 and 13 which are mounted upon the stud 23 I preferably provide annular flanges 31 and 32 extending in opposite directions to provide journal bearings for the arms. Preferably also 20 the stud 23 has a collar 33 against which the end of the flange 31 of the yoke 12 is arranged to bear so that the gear segment 27 of said yoke may be maintained in meshing 25 engagement with the pinion 11. Like the yoke 12 the yoke 13 has an arcuate portion 13^a which is cut to provide a slot 34, and one edge of this slot is provided with gear teeth 35 to form a gear segment adapted to 30 mesh with the pinion 11 on the side opposite that engaged by the segment 27 of the yoke 12.

35 The operating lever 14 is fixed upon the stem 22 so that by means of the thumb of 40 the hand of the operator which carries the knotter, the stem may be rotated. For this purpose, the stem 22 extends outwardly beyond the side wall of the casing 8, being 45 reduced in diameter to provide a shoulder 36 against which the inner end of the operating lever is clamped by means of a clamping screw 37 entered into the stem 22 from the outer end thereof. It will be seen that the stem 22 and the screws 29 and 37 50 carried thereby together constitute a rotatable element adapted to be turned by operation of the lever 14.

55 Between the lever 14 and the adjacent wall of the casing 8 is a plate 38. Said plate is suitably apertured to receive the stem and is fixed to the casing in any suitable way. Said plate has at its lower end a strap carrying member 39 of usual construction and at its upper end has a portion 40 projecting upwardly beyond the periphery of the casing so as to provide a thread guide arranged to cooperate with the clamping stripper 15 and the guide 16 at the opposite side of the casing.

60 65 The clamping stripper 15 is mounted to

swing upon the stem 22 and has a rigid connection with the yoke 13. Such connection may comprise a plate 41 fixed to one arm of the yoke 13 and rotatably mounted on the head 28 of the screw 29. Said plate 70 is approximately semi-circular in form (Fig. 3). The plate 41 is made of a diameter slightly less than the interior of the casing, and at its peripheral edge it is shaped to provide a flange 42 having an opening 75 42^a (Fig. 4) for neatly receiving the clamping stripper. The clamping stripper, it will be understood, is arranged to project from the casing a substantial distance, the latter being provided with an arcuate slot 80 43 (Fig. 4) for receiving the stripper. Said slot it will be apparent is arranged to be closed by the flange 42 which is made of a length sufficient to close the slot irrespective of the position of the yoke 13 in 85 the casing. In order to permit of the relative movement between the flange 42 swingable in one direction with the yoke 13, and the yoke 12 movable in the opposite direction, the plate 41 is slotted near its periphery as at 44 and 44^a (Fig. 3) so as to receive the opposite ends of the arcuate portion 12^a of the yoke 12.

90 Said stripper may comprise two elongated members or plates 45 and 46 and an intermediate member 47. The members 45 and 46 at their lower ends are mounted for rotation upon a journal 48 provided by the stem 22, and the upper ends of said members are shaped to provide stationary jaws 49 100 with which a clamping jaw 50 provided by the upper end of the intermediate member 47 is arranged to coact in the operation of the knotter. Preferably the plates 45 and 46 are formed from an integral piece of 105 sheet metal, being connected at their rear edges by a web portion 46^a, shown in section in Fig. 4. In its lower portion the intermediate member 47 is provided with an elongated opening 51 (Fig. 4) for receiving the stem 22, and at its lower end said member carries a roller stud 52. This stud is arranged to lie within a cam groove 53 (Fig. 4) provided in the cam member 17 110 which is fixed to the adjacent wall of the 115 casing. By reference to Fig. 4 it will be seen that the cam groove 53 is so shaped that at each end of the swinging movement of the stripper the movable jaw is in inoperative or releasing position, but that during a substantial portion of such swinging movement the said jaw is held in position to clamp the thread or yarn.

120 The thread guide 16 upon the side of the casing opposite the clamping stripper 15 125 may be of any preferred construction, being herein approximately circular in shape and having at its upper end a notched portion to provide a hooked guide 54 for the threads or yarn. The guide member 16 is rigidly 130

secured to the casing 8, in any suitable manner, being apertured at its center to receive the stud 23. Preferably the plates 16 and 38 on opposite sides of the casing are shaped 5 to provide rounded forward edges 16^a and 38^a (Fig. 1) upon which the threads may ride so as to facilitate the positioning thereof for the tying operation.

The spring 18 for returning the parts to 10 initial position after movement by the operating lever 14 may be in the form of a flat coil one end of which is fixed as at 55 (Fig. 2) to the head 28 of the screw 29 inserted into the inner end of the stem 22. 15 The opposite end of said coil is preferably connected with the driven yoke 13 as at 56 (Fig. 3).

The operation of the knotter will, it is believed be readily understood from the foregoing description. By way of summary, 20 however, the operation is briefly as follows:

With the parts in the position shown in the drawings, the two strands of thread or 25 yarn to be united are passed over the guide 40, through the clamping stripper 15 and into operative relation with the tying-bill 10 in a well known manner, and thence through the hooked guide 54 of the member 16. Thereupon an operation of the lever 30 14 swings the driving yoke 12 in one direction, rotating the spindle 9 and swinging the driven yoke 13 in a direction opposite to that of the yoke 12. The size of the yoke 13 is so proportioned as to impart to the 35 clamping stripper 15 a stroke of the desired length. With the spindle 9 the tying-bill 10 rotates to form the loops of the knot, clamp the threads, and sever the ends thereof, and the clamping stripper 15 in its 40 swinging movement operates to clamp the threads and as it continues to swing, strip the loops from off the tying-bill while the ends remain clamped thereby. As the stripper 45 nears the end of its stroke, the knot becomes tightened, and finally the ends of the thread are withdrawn by the stripper from the tying-bill. After the knot has thus been formed, the clamping stripper is operated by the cam member 17 to release the thread 50 ends held thereby.

It will be observed that I have provided a knotter of advantageous construction. The arrangement of the mechanism is very 55 compact, and by reason of the fact that the device is made almost wholly from sheet metal, it may be manufactured at a very low cost. Moreover, the construction is of such a rugged character that the knotter is capable of withstanding long and hard 60 usage.

I claim as my invention:

1. A knotter comprising, in combination, 65 a supporting structure, a spindle journaled therein, a tying bill at one end of the spindle, thread-guiding means on the support-

ing structure, a rotatable stem journaled in the supporting structure, a driving member fixed to said stem and having an operative connection with said spindle to rotate it, a member relative to which said stem is 70 adapted to rotate and having a gearing connection with the spindle, and a device connected with the last mentioned member whereby a rotation of said spindle effects a relative swinging movement between the 75 tying bill and said device to strip the looped thread from the tying bill.

2. A knotter comprising, in combination, 80 a stationary annular casing, a spindle extending diametrically of the casing and having a tying bill at one end projecting through one wall of the casing, thread guiding means carried by the casing, a rotatable stem journaled in the casing, a driving member fixed to said stem and having an operative connection with said spindle to rotate it, a member relative to which said stem is 85 adapted to rotate and having a gearing connection with the spindle, and a device connected with the last mentioned member whereby a rotation of said spindle effects a relative swinging movement between the tying bill and said device to strip the looped thread from the tying bill.

3. A knotter comprising, in combination, 90 a supporting structure, a spindle journaled therein, a tying bill rotatable with said spindle, a clamping stripper mounted for swinging movement relative to the supporting structure and the tying bill, a pair of 100 yokes having a common axis in said supporting structure and each having a gearing connection with said spindle, means for actuating one of said yokes to drive the spindle and thereby the other yoke, and means 105 connecting the last mentioned yoke with the clamping stripper.

4. A knotter comprising, in combination, 110 a stationary casing having a tying bill projecting from one wall thereof, thread guiding means rigid relative to the casing and positioned laterally of the tying bill, a clamping stripper swingable relative to the casing and said tying bill, actuating mechanism enclosed within the casing comprising a rotatable element journaled in the casing, and means operatively associated with said element for rotating the tying bill and swinging said stripper, said stripper being 115 rotatably mounted on said element and there being a slot in the casing through which the stripper extends.

5. A knotter comprising, in combination, 120 a casing, a spindle mounted for rotation in the casing and having a tying bill at one end projecting from one wall of the casing, a clamping stripper mounted for swinging movement relative to the casing and said 125 tying bill comprising relatively fixed and movable members, and means within the cas-

ing for rotating said tying bill and actuating the clamping stripper including a rotatable element, a pinion on said spindle, a driving member rigid with said element and having a gearing connection with the pinion, a driven member also having a gearing connection with said pinion and being rigid with said clamping stripper, and mechanism actuated in the rotation of said element for actuating the movable member of the clamping stripper.

6. A knotter comprising, in combination, an annular casing, a spindle journaled in the casing and extending diametrically thereof, a tying bill rotatable with said spindle, a clamping stripper mounted for swinging movement relative to the casing and the tying bill, a pair of interfitting yokes mounted coaxially of the casing and each having a gearing connection with said spindle, means for actuating one of said yokes to drive the spindle and thereby the other yoke, and means connecting the last mentioned yoke with the clamping stripper.

7. A knotter comprising, in combination, a casing, a spindle journaled in the casing and having a tying bill at one end thereof, a pair of yokes coaxially mounted relative to each other in the casing and each having a gearing connection with said spindle, an element rotatable with one of said yokes, a clamping stripper swingable with the other one of said yokes, an operating lever for rotating said element in one direction, and spring means for rotating the element in the opposite direction.

8. A knotter comprising, in combination, a casing, a spindle journaled in the casing, a tying bill rotatable with said spindle, a pair of actuating yokes each having a gearing connection with the spindle, a rotatable element with which one of said yokes is rigid, a swingable element with which the other one of said yokes is rigid, and means for actuating said rotatable element whereby to rotate said spindle and swing the swingable element.

9. A knotter comprising, in combination, a casing, a tying bill, a pair of actuating yokes one of which is operatively associated with the tying bill to rotate it, a clamping stripper operatively associated with the other one of said yokes so as to be swung thereby relative to the casing and said tying bill, said yokes being operatively associated so that movement imparted to one of them in one direction will swing the other one of them in the opposite direction, and means for swinging one of said yokes.

10. A knotter comprising, in combination, a supporting structure, a tying bill, a pair of actuating yokes one of which is operatively associated with the tying bill to rotate it, a clamping stripper operatively associated with the other one of said yokes so as to be

swung thereby relative to the supporting structure and said tying bill, said yokes being operatively associated so that movement imparted to one of them in one direction will swing the other one of them in the opposite direction, and a thumb lever attached to one of said yokes.

11. A knotter comprising, in combination, a casing, a spindle mounted in said casing, a tying element rotatable with the spindle, a stripping element, and means for effecting relative swinging movement between the tying element and the stripping element comprising a rotatable member journaled in the casing, an actuating member fixed with reference to said rotatable member and operatively connected with the rotary tying element, and a second actuating member operatively associated with the first mentioned actuating member and with the stripping element.

12. A knotter comprising, in combination, a casing, a spindle journaled in the casing having a rotary tying element at one end, a stripping element, and means for effecting a relative swinging movement between the tying element and the stripping element comprising a rotatable element, a pair of interfitting yokes each having a gearing connection with said spindle, one of said yokes being rigid with said rotatable element and the other one of said yokes being rigid with said stripping element, an operating lever for rotating said rotatable element in one direction, and spring means for rotating the element in the opposite direction.

13. A knotter comprising, in combination, a casing, a spindle journaled in the casing having a rotary tying element at one end, a stripping element, and means for effecting a relative swinging movement between the tying element and the stripping element comprising a rotatable element, a pair of interfitting yokes each having a gearing connection with said spindle, one of said yokes being rigid with said rotatable element and the other one of said yokes being rigid with said stripping element, an operating lever for rotating said rotatable element in one direction, spring means for rotating the element in the opposite direction, said stripping element comprising two relatively movable members, and cam means operable in the rotation of said rotatable element for actuating the movable member of the stripping element.

14. A knotter comprising, in combination, an annular casing, a spindle journaled in the casing diametrically thereof, a bearing stud and an operating stem mounted coaxially of the casing at opposite sides of said spindle, a pair of actuating members interfitting and mounted on said stud and stem, said spindle having a pinion rigid therewith and

5 said actuating members each having gear teeth meshing with said pinion, one of said yokes being rigid with said stem, a clamping stripper rotatably mounted on said stem and fixed with reference to the other one of said yokes, and means for rotating said stem.
